Patented Aug. 30, 1927.

UNITED STATES PATENT OFFICE.

WILLIAM G. HOSKINS, OF NEW YORK, N. Y., ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed October 30, 1922. Serial No. 597,748.

This invention relates to electron discharge devices and pertains especially to the electrode structure thereof.

An object of the invention is an electrode structure wherein lateral wires, such as the turns of a wire helix are attached to a plurality of supporting members by tie wires.

Another object of the invention is a method of manufacture of an electrode in accordance with which lateral wires are tied to frame members.

These objects are attained by providing a supporting member to which lateral wires are tied by means of one or more sinuous lengths of wire, the alternate bends of which pass over the lateral wires and the remaining bends of which pass behind the supporting member. Preferably the lateral wires are attached to the supporting member by means of a tie member comprising a pair of sinusoidal lengths of wire, the alternate bends of which are linked together behind the supporting member and the remaining bends of which bind the lateral wires against the supporting member.

The tie member is formed by winding a double coil of parallel wires and pressing it into a plane or other desired surface, thus forming two interlinked sinusoidal shaped pieces of wire. The wires are moved laterally with respect to each other to bring the links in contact, and the tie member is then laid on the helix which is to be tied to the supporting members with its outer bends resting on the turns of the helix and its interlinked portions lying within the helix. A supporting wire is then forced between the helix and the interlinked portions of the tie member, thus securing the turns of the tie member to the supporting member. The grid helix to the supporting member. The tie member clamps the turns of the grid helix securely against the supporting member thereby preventing the turns of the helix from springing away from the supporting member, and the interlinked portions of the tie member serve to space apart the adjacent turns of the grid helix. This type of electrode has the advantage that no welding operation is required in its manufacture.

Referring now to the drawings, Fig. 1 discloses an electron discharge device having a grid electrode constructed in accordance with the invention; Fig. 2 is an enlarged detail between the lines AA and BB of Fig. 1; and Figs. 3 to 7 inclusive disclose

the successive steps in the process of manufacture of the grid electrode, Fig. 7 being on a larger scale.

The grid structure comprises a plurality of supporting wires or rods 10 from which is supported the enclosing grid helix 11. The turns of the helix 11 are clamped against the supporting wires 10 by two continuous sinusoidal tie wires 12 which pass over each turn of the helix and are interlinked behind the supporting wires intermediate the successive turns. The tie wires effectively bind the turns of the helix against the supporting rods and prevent slippage of the grid wires. The portions of the tie wire which form the interlinkings behind the supporting wire serve to determine the space relation between the adjacent turns of the helix 11.

As disclosed in Figs. 3 to 6 inclusive, the method of constructing the grid is as follows:

A tie member is formed by winding two fine wires 12 in parallel on a mandrel as shown in Fig. 3 to a definite pitch and a definite number of total turns. The ends of the wires 12 are twisted together at each end of the double helix as shown at 14 in Fig. 3, so that there will be exactly the same number of turns in each coil after the tie member has been allowed to back off on the mandrel. The double coil thus formed is stretched to a definite length and is then flattened between two parallel surfaces into the shape shown in Fig. 4. This reduces the double coil to a pair of sinusoidal shaped lengths of wire which alternately pass over and under each other. The wires are now moved apart laterally as shown in Fig. 5 until the bends 15 of one wire engage the bends 16 of the other, forming interlinkings 17 at each complete cycle, and the bends 18 of the first wire being opposite the bends 19 of the second.

The grid wire 11, as shown in Fig. 6, is wound on a collapsible jig 20 having a plurality of longitudinal slots 21, to form a helix of the desired size and having the proper space relation between its turns. A tie member is then laid on the helix 11 along each slot 21 with each set of opposed bends 18 and 19 resting on a turn of the helix 11 and the interlinkings 17 lying within the periphery of the helix. A supporting wire 10 having a pointed end 22 is then threaded

between the turns of the helix 11 and the interlinked portions of the tie member. The introduction of the supporting wire causes the tie member to assume the position shown in Fig. 7 and binds the turns of the helix 11 against the supporting wire 10. The jig 20 is now collapsed and the grid removed therefrom after which the latter is assembled with other electrodes as shown in Fig. 1.

10 The invention claimed is:

1. In an electron discharge device, an electrode comprising a frame member, a wire helix, and a pair of wires alternately passing over the turns of said helix and being fastened to each other behind said frame member.
2. In an electron discharge device, an electrode comprising a frame member, a wire helix, means for binding said helix to said supporting member comprising a pair of sinuous wires passing over the turns of said helix and being interlinked behind said frame member.
3. In an electron discharge device, a frame member, a wire helix, and a pair of tie wires alternately passing over the turns of said helix and being interlinked with each other behind said frame member.
4. In an electron discharge device, a supporting member, a wire helix, and a sinusoidal length of wire having its alternate bends passing over the turns of said helix and the remaining bends fastened behind said supporting member.
- 35 5. In an electron discharge device, a frame member, a wire helix, and a pair of sinusoidal lengths of wire each having its alternate bends passing over the turns of said helix and having the remaining bends passing behind said frame member.
- 40 6. In an electron discharge device, a frame member, a wire helix, and a pair of sinusoidal shaped lengths of wire each having its alternate bends passing over the turns of said helix and the remaining bends joined together behind said frame member.
- 45 7. In an electron discharge device, a supporting member, a wire helix and a pair of interlinked sinusoidal shaped lengths of

wire, the interlinked portions lying behind 50 said supporting member and the remaining portions passing over the turns of said helix.

8. The method which comprises forming a tie member composed of a pair of interlinked sinusoidal lengths of wire, laying said tie member along a wire helix with its free bends lying on the turns of said helix, and passing a rod between the turns of said helix and the interlinked portions of said tie member.

9. The method which comprises interlinking two sinusoidal shaped lengths of wire, laying the same on a wire helix with the free bends engaging the turns of the helix, and passing a rod between said turns and 65 said interlinked portions.

10. The method of forming a tie member which comprises winding two wires in parallel to form a double helix and flattening said double helix to form a pair of sinusoidal shaped lengths of wire interlinked at each complete cycle.

11. The method which comprises forming a double coil, flattening said coil, moving the wires of said coil laterally, laying said wires 75 on a helix with the opposed bends thereof resting on the turns of said helix, and passing a rod between the turns of said helix and the interlinked portions of said tie member.

12. In combination, a frame member, a helix, and means for supporting said helix from said frame member comprising a pair of tie members passing alternately over said helix and interlinking behind said frame member.

13. In combination, a frame member, a helix, and means for supporting said helix from said frame member comprising a pair of sinusoidal lengths of wire, each having 90 its alternate bends passing over said helix and the remaining bends interlinked behind said frame member.

In witness whereof, I hereunto subscribe my name this 27th day of October, A. D., 95 1922.

WILLIAM G. HOUSKEEPER.
